UNITED STATES PATENT OFFICE.

JAMES M. MORGAN, OF PORT WASHINGTON, WISCONSIN.

DESIGN FOR A STOOL OR CHAIR IRON.

SPECIFICATION forming part of Design No. 24,946, dated December 3, 1895.

Application filed November 4, 1895. Serial No. 567,952. Term of patent 14 years.

To all whom it may concern:

Be it known that I, JAMES M. MORGAN, of Port Washington, in the county of Ozaukee and State of Wisconsin, have invented a new and original Design for a Stool or Chair Iron, of which the following is a description, reference being had to the accompanying drawings, which are a part of this specification.

Figure 1 is a plan view of a stool or chair iron, showing my design. Fig. 2 is a side elevation of the same, and Fig. 3 is a cross-section through one of the arms.

The leading feature of my design is the general shape and configuration of a stool or chair iron, as herein shown and described, whereby a particularly ornate effect is produced in this class of articles.

A is the central hub of the iron, which is cylindrical in its general contour, and B are the arms radiating from the hub. The outer ends of these arms terminate in circular enlargements C, which enlargements intersect the ends of the arms vertically and are disposed obliquely thereto at an outward incline. The tops or upper ends of the enlargements are convex or rounded, as clearly shown. The arms B curve downwardly throughout their length, and the general form thereof longitudinally is V shape in cross-section, the sides being slightly convex and converging to the central longitudinal apex D, as clearly shown in Fig. 3. In this figure the under side of the arm is shown concave. This is an immaterial feature, however, inasmuch as, so far as the design is concerned, the under side may just as well be solid. The upper edge or apex of each arm, where said

edge or apex merges into the central hub, is widened or spread out somewhat and reversely curved or convexed, as indicated at E, thereby obviating the ornate effect which would be produced if the apex joined the hub abruptly and sharply. The lines of the sides of the arms are also changed at the points of merging into the hub, being given a slight inward curve, as indicated at F, the cylindrical surface of the hub between these slight inward curves forming a series of surface delineations or effects of approximate V shape, as indicated at G. The lower angles of these V-shaped figures are the points where the several legs begin to merge into each other.

It will be noticed that the lower edges of the sides of the arms are provided with longitudinal beads or ridges H H, the inner ends of opposite beads or ridges of adjacent arms curving around and joining each other, as indicated at I.

In order to prevent sharp junction lines at the points where the arms B merge into the enlargement C, the sides of said arms at such points are swelled slightly and concaved, as indicated at J. The curves of the beads or ridges H H also blend with the curves of the enlargements, so as to obviate any sharp lines.

What I claim is—

The design for a stool or chair iron, substantially as shown and described.

In testimony whereof I affix my signature in presence of two witnesses.

JAMES M. MORGAN.
